UNITED STATES PATENT OFFICE.

FRANK E. JACKSON AND RICHARD A. WALLINGFORD, OF BAKERSFIELD, CALIFORNIA.

GAS BURNER.

Application filed February 15, 1923. Serial No. 619,077.

Our present invention relates to gas burners; and it is a special object of our invention to provide a burner and an assembly of burners superior to those which are in current use in, for example, the heating of steam boilers by the combustion of natural gas.

It is an object of our invention to provide a combination of horizontal and inclined burners in such relative positions and of such size and form as to get a maximum heating effect and at the same time eliminate blowpipe effects upon heating surfaces; and we accomplish our results without the use of baffles, checkerwalls, or other arrangements tending to a retardation of draft or a wastage of heat.

It is a further object of our invention to provide burner assemblies favorably placed with reference to a boiler or other surface to be heated and in which one set of burners may be utilized to knock the top off from the flames of another set of burners; and, in this connection, we ordinarily prefer to employ a limited number of horizontal burners of high velocity to spread the flame and consequent heat from an assembly or assemblies of inclined burners placed at an angle to the horizontal burners.

A further object of our invention is to provide a new method of burning fuel in a furnace by injecting jets of fuel in an inclined direction, giving a series of flames, blowing towards the furnace or object to be heated and at the same time blowing a strong jet or jets of fuel giving flames of high velocity, substantially horizontally so that the upper flames impinge on the tops of the inclined flames blowing the tops off and preventing a blow pipe effect on the boiler or object heated.

It is a further object of our invention to provide means whereby the respective sets of burners referred to may be separately controlled so that one set may alternatively be used alone, or may be used for preliminary heating, or may be used in other cooperative relationships herein described.

It is a further object of our invention to include an aperture permitting the introduction of an oil burner; and we prefer to utilize the mentioned aperture in effecting the ignition of one set of burners, this set

being preferably so arranged as to be capable of igniting an additional set or sets.

It is a further object of our invention to provide means favorable to a reignition of our burners in case of a momentary interruption of a supply of gas thereto.

It is a further object of our invention to provide individual burner units which shall deliver and mix air and gas in suitable proportions and which shall be durable but nevertheless capable of easy insertion and removal.

It is a further object of our invention to associate with our burner units suitable fire-resistant protective materials, such as fire-clay or plastic fire-brick, suitably molded; and we prefer to so mold the mentioned materials as to form expanded continuations of the mixing passages provided by the metallic portions of our burners, the construction being such that the velocity of the gases may be suitably reduced, and the resultant flames may be kept at a moderate level, the heating effect being favorably distributed.

It is a further object of our invention to provide castings into which our burner units may be easily and securely fitted, these castings being preferably made in separate sections which are adapted to be assembled in any desired number; and we prefer to so form these castings that they may support the individual burners or burner units at an angle and at the same time afford a suitable foundation for the plastic material which we prefer to mold thereon, to provide flaring extensions at the exit ends of our respective burners.

Further objects of our invention will appear from the following description and the appended claims.

It is believed that the general character of the organization in which we employ our burners; and also the preferred character of the burners themselves and the parts associated therewith, will be apparent from the following description of preferred embodiments of our invention, taken in connection with the accompanying drawings, in which

Fig. 1 is a front or end elevation of an installation disclosing our invention, parts being broken away.

Fig. 2 is a vertical section taken at right angles to Fig. 1.

Fig. 3 is a view showing a preferred type of supporting castings to which our burners may be secured.

Fig. 4 is an enlarged detail view showing 5 completely but one burner unit of a preferred type.

Fig. 5 is an enlarged detail view on the line 5—5 of Fig. 4, showing the bayonet connection by which each of our burner 10 units may be supported in a suitable aperture formed by gaps in supporting castings which are preferably laid edge to edge, as best shown in Fig. 3.

Fig. 6 is an enlarged detail view on the 15 line 6—6 of Fig. 4.

Figs. 7 and 8 are diagrammatic representations of alternative embodiments of our invention.

Referring in detail to the form shown in 20 Figs. 1 to 6 inclusive, it will be understood that 1 is a boiler or other receptacle to be heated, this boiler being supported by known means or by the end walls 2, and heat being confined by means such as the 25 lateral walls 3. Adjacent the front wall we may provide a valved inlet pipe 4 for the introduction of natural gas by the branch pipes 5 and 5' to a series of high velocity burners 6. By means of, for example, 30 valved extensions 7 and 7' we may carry an additional quantity of gas through a manifold M and suitable connections 8, 9 and 9' to a main set of burners 10.

The individual units comprising the mentioned main set of burners are preferably 35 of simple construction, and each may comprise a cylindrical element 11 flared at its receiving end 12 to provide for an ample intake of air and provided at its opposite 40 end with means for engagement with any suitable supporting means, lugs to provide a bayonet connection being shown at 14, and a circumferential collar at 15. It will be understood that the pipes and fittings by 45 which the gas is led to the respective burners may be, for example, standard malleable fittings, and that the gas is delivered to each burner through an aperture 16 at or near the center of the base thereof, the parts 50 referred to being held in their desired relationships by means of the apertured webs 17 at the base of the respective burner units.

As a convenient means for the support of 55 the respective burner elements or units in their assembled relationship, we prefer to provide castings 18, which are preferably formed of identical units adapted to be placed edge to edge in any desired number, the units being respectively provided with 60 gaps 19 which, when a plurality of these elements are suitably assembled, are adapted to receive and support a corresponding number of rows of the mentioned burner elements, notches 20 being provided in the castings to permit of the insertion of the

lugs 14 upon the respective burner elements, and the distance between the lugs 14 and the collars 15 being adapted to the thickness of the supporting plates, as best shown in Fig. 4.

Whether or not our burners are set, as we prefer to place them, at an angle relative to the surface to be heated, we prefer to provide extensions of the mixing chambers thereof by suitably molding upon the assembled castings 18 a fire-resistant material such as plastic fire-brick 18^a, imparting thereto such a configuration as shall provide an expansion at the exit end 21 of each mixing chamber, this expansion preferably 75 to be such that the area at the exit shall be substantially greater than the cross section of each burner at its narrowest point: for example, four times that area.

By the construction referred to, it will be 80 understood that we effect a relative retardation of the gaseous mixture, softening the character of the flame projected by the set of burners referred to, this result being attained without any diminution in the heating effect thereof. To enable a set of inclined burners to be supported in the manner best shown in Fig. 2, we may provide the castings 18 with horizontal extensions 22 and 23, respectively adapted to be built into, for 85 example, the front wall and the floor of a furnace; and we may construct the floor referred to of separate units 24 of fire-resistant material supported by any suitable means 90 such as the I-beams 25.

As already mentioned, the preferred embodiment of our invention involves the provision of a set of auxiliary or high velocity burners 6, shown as extending through the front wall of a furnace, and unprovided 105 with the mentioned flaring extensions of their respective mixing chambers, it being our intention that these auxiliary burners shall produce an intense horizontal flame, adapted to knock the top off from the flames 110 produced by the main body of burners already described and referred to as inclined burners. The construction referred to has been found very advantageous, as tending to a uniform distribution of a very high 115 temperature and the avoidance of a blowpipe effect anywhere within a furnace of our preferred construction. Immediately in front of the auxiliary set of the high velocity horizontal burners 6, we find it advantageous to 120 provide a set of heat retaining bodies such as the fire-bricks 26 set on edge, as shown in Figs. 1 and 2, these fire-bricks being preferably placed in the intervals between the flames from the auxiliary burners, and immediately above the respective series of inclined burners, the latter being shown as staggered in their relationship to the mentioned auxiliary burners.

To permit the use of an oil burner in case 125

of, for example, interruption of gas supply, we prefer to provide an aperture 27, through which an oil burner may be inserted; and we may use this aperture also in the igniting of the auxiliary burners 6, it being practicable to insert a suitable torch through the mentioned aperture. It will be understood that, as occasion may require, we may use the auxiliary burners 6 either as a sole 10 means of heating, or as a means for the igniting of the inclined burners, or as a means for warming up, or as a means for suitably deflecting the flames of said inclined burners.

15 It will also be understood that, while we have shown the high velocity burners as arranged horizontally and substantially cylindrical, they may be arranged at any suitable angle, and an actual choke effect may be provided by constricting the outlet therefrom, to impart a higher velocity to the resulting flame.

20 In Fig. 7 we have disclosed one of the innumerable alternative constructions in which our invention may be embodied. In this 25 form of our invention we may employ two main sets 28 and 29 of burners, similar to those shown in Fig. 2, and set at an angle suitable to the existing conditions, these 30 sets being suitably spaced apart, and having their tops knocked off by a plurality of flames from the high velocity burners 30 and 31, the latter of these being adapted to project its flame slightly downward, and 35 suitable regulating valves for the respective sets of burners being shown at 32, 33, 34 and 35.

40 In Fig. 8, we have shown an alternative construction in which no high velocity burners are employed, two main sets of burners being oppositely inclined, so that each has a 45 deflecting effect upon the flames from the other, this arrangement being especially advantageous when a strong central heating is required.

45 In the use of the last-mentioned form of our invention, the respective sets of burners may be controlled by means such as the valves 36, 37, and it should be understood that in all cases where we employ sets 50 of burners fixed in groups such as are shown in Figs. 1, 2, 7 and 8, we prefer to bring the gas to both ends of the manifold thereof, in order to be able to equalize the pressure 55 throughout the set; and we may also provide means such as the valved pipe 38, shown in Fig. 2, for the withdrawal of oily deposits.

60 It will be seen from the above description that we have developed a novel method of 65 burning fuel shown in connection with a boiler but that the principles involved have many general uses.

65 In brief the method may be described as injecting combustible jets at an angle form-

ing flames having comparatively slow velocity in an inclined direction and blowing jets of fuel having flames of a high velocity so as to impinge on the tops of the flames of low velocity, having the so-called effect 70 of blowing their tops off and preventing actual contact of the inclined flames with the boiler or object to be heated. This prevents the so-called and injurious blow torch effect.

75 Our method may be utilized as shown in Fig. 2 with a single bank of inclined burners and with a single set of horizontal burners injecting fuel of high velocity as shown in Fig. 2, or two or more banks may be 80 utilized as in Fig. 7 with two or more substantially horizontal or slightly downwardly inclined blow torch jets impinging on the inclined jets.

85 It is obvious also that our method of burning fuel in this manner may be applied to oil jets as well as gas jets in that after the oil is ignited the reaction will be between jets of burning gases and not between solid oil jets, therefore the effect will 90 be much as described above.

95 It is also obvious that for certain purposes the jets of slow velocity could be inclined downwardly and the jets of high velocity be blown below such jets impinging on the flames and thereby changing their direction. This type of flame may be utilized for casting heat principally downwardly.

100 Many other modifications of our principle or method it is believed will be obvious.

105 It will be understood that various features of our invention may be independently used, and also that various modifications will be possible without departure from the spirit and scope of our invention, as the same is indicated above and in the following claims.

110 What we claim is:

1. A burner mounting having an inclined wall, the said wall being formed of a series of bars, each bar having recesses in its edge with notches formed in the recesses and notches of adjacent bars registering to form 115 gaps therethrough, the set of bars forming a substantially flat wall surface and a series of cylindrical burners having segmental lugs at their ends adapted to pass through the said notches in the assembled 120 bars forming a bayonet type connection, a collar fitting against the outside surface of the bars, and a molding of plastic fire resisting material formed on the bars between the burners, said material being molded to 125 form flared discharge nozzles, the material between the adjacent nozzles meeting in a pointed edge.

2. A burner mounting comprising a series of castings in the form of bars, each 130

bar having a series of recesses, the recesses being positioned to register with adjacent bars, the bars forming substantially a flat surface with gaps therethrough, a series of 5 cylindrical burners secured in said gaps, and a molding of plastic fire resisting material formed on the bars between the burners, said material being molded to form

flared discharge nozzles, the material between the adjacent nozzles meeting in a 10 pointed edge.

In testimony whereof we have signed our names to this specification.

FRANK E. JACKSON.
RICHARD A. WALLINGFORD.
